UNITED STATES PATENT OFFICE.

SAMUEL B. WILLIAMS, JR., OF BROOKLYN, NEW YORK, ASSIGNEE TO WESTERN ELECTRIC COMPANY, INCORPORATED, OF NEW YORK, N. Y., A CORPORATION OF NEW YORK.

RECORDING MECHANISM.

Application filed October 26, 1922. Serial No. 598,923.

To all whom it may concern:

Be it known that I, SAMUEL B. WILLIAMS, Jr., a citizen of the United States, residing at Brooklyn, in the county of Kings and State of New York, have invented certain new and useful Improvements in Recording Mechanisms, of which the following is a full, clear, concise, and exact description.

This invention relates to recording and selecting mechanisms and more especially to such mechanisms when adapted to telephone exchange systems.

The object of the invention is an improved recording and selecting equipment comprising a plurality of counting devices such as relays operative in response to impulse series representing designations.

A feature of the invention relates to a series of counting relays arranged for successive operation, a plurality of said relays each releasing on operation of the succeeding relay and wherein a particular one of said relays being operated remains operated until a plurality of succeeding relays are actuated.

Such other features as are contemplated by the present invention will become more clearly understood from the following detailed description and from the appended claims.

Referring to the drawing, Figs. 1 and 2 taken together illustrate enough of a telephone exchange system to enable an understanding of the features of the invention. Fig. 1 discloses two subscribers' lines terminating in a line switch at the central office, other switches for extending the line, together with the details of an impulse receiving and selecting mechanism. Fig. 2 shows in full, two separate relay register devices each for receiving and recording a different portion of a designation. At the right of this figure, there is also illustrated, in schematic form, an additional register for recording another part of the designation.

In telephone systems of the automatic and semi-automatic type, it is sometimes desirable to register on apparatus at the central office, the designation of the wanted line or circuit. This registration serves to govern the selective operations of switches to extend the required connection or for controlling the operation of indicating mechanism

which enable an operator to extend or complete the desired call. It is in a system of this general character that the recording mechanism embodying the features of applicant's invention is particularly useful. Obviously, however, the invention is applicable in its broadest aspects to any system wherein it is desired to establish a record by means of designation impulses.

In the system disclosed, the subscribers' lines, such as lines 100 and 101, extend to the central office and terminate in a line switch 102, diagrammatically shown. The line switch 102 is adapted to extend the calling line to any of a number of trunks, one of which, trunk 103, 104, is illustrated, leading to a first selector switch 106. Switch 106 may be of the same character as the line switch 102 and has for its function to extend the incoming trunks to outgoing trunks. Several of the outgoing trunks 107, 108, 109, 110, 111 and 112 are illustrated. Obviously, these outgoing trunks may lead to succeeding selective switch devices where they are again selectively connected to other trunks and so on until the connection is completed.

Also, located at the central office is an impulse receiving and recording mechanism comprising an organization of relays and circuits, the function of which is to receive the impulses transmitted from the calling line and record the designations represented by these impulses. There may be any desired number of recording mechanisms for serving a group of subscribers' lines, the particular one to be taken for use at any one time depending upon its busy or idle condition. A selective switch 105 is provided for associating an idle one of the recording mechanisms with a particular trunk 103, 104 to which the calling subscriber's line has been connected.

The switches 102, 106 and 105 may be of the coordinate type such as generally shown and described in detail in the patent to S. B. Williams, No. 1,517,331, issued December 2, 1924. For an understanding of one method of controlling switches of this character in a telephone system, reference is made to the circuit descriptions found in said patent to S. B. Williams. Furthermore, these switches may be of any well known and ap-

proved type, such as power driven selectors or selectors in which multi-contact relays are employed, for building up connections with means for selecting and operating the necessary relays.

A detailed description will now be given of the operation of the system. Assume, for example, that the subscriber of line 100 wishes to make a call to a line, the designation of which, is represented by a number having the first two digits 2 and 3. Each of these digits is represented by a separate series of impulses transmitted over the line which are received by the counting relay set 126 shown in Fig. 1 and recorded successively on the respective registers 200 and 201 shown in Fig. 2. When the calling subscriber initiates the call by removing his receiver from the switchhook, the line switch 102 operates to extend the line 100 to an idle trunk 103, 104. Moreover, the selecting switch 105 operates to associate the idle recording mechanism shown with the selected trunk 103, 104. In response to these operations, a circuit is closed from battery over conductor 147, resistance 117, left-hand winding of impulse relay 115, through contacts of the selector switch 105, trunk conductor 104 through contacts of the line switch 102 over the subscriber's line 100 and returning through the contacts of line switch 102, trunk conductor 103, contacts of the selector switch 105, through the balancing coil 118 to ground. Relay 115 operates and at its right contact closes a circuit for the slow-to-release relay 119. Relay 119 at its left contact, applies ground potential to the holding conductor 146, for maintaining the various relays operated. Relay 119 also closes a circuit from battery through the resistance 116, right-hand winding of relay 120 to ground at the right contact of relay 119. Relay 120, however, does not operate in this circuit so long as relay 115 remains energized to maintain the following shunt path around the right-hand winding of relay 120: battery, through the resistance 116, left contact of relay 115, left contact of relay 119 to ground.

When the subscriber operates his transmitter 150 to send two impulses constituting the first series, the impulse relay 115 deenergizes twice in succession. On the first deenergization of relay 115, the shunt circuit around relay 120 is opened and this relay immediately operates. Relay 120 locks momentarily in a circuit from battery, through its left-hand winding and inner left contact, outer right back contact of relay 121 to ground over conductor 146. Relay 120 also closes a circuit from battery through the left-hand winding of relay 121 to ground at the inner right contact of relay 120. Relay 121 operates and locks in a circuit from battery, through its right-hand winding and inner right contact to the grounded conductor

146. Relay 120 also completes a circuit from ground over conductor 146 through its outer right contact, winding of relay 123 to battery. Relay 123 energizes and locks in a circuit from battery through its winding 70 and upper front contact, upper contact of relay 124 to ground over conductor 146.

At the time relay 119 is operated, it closes a circuit from battery through the winding of slow-to-release relay 122, upper back contact of relay 123, upper contact of relay 124, conductor 146 to ground at the left contact of relay 119. Relay 122 operates in this circuit and is held in the following circuit after relay 123 becomes energized: battery, 80 through the winding of relay 122, outer right front contact of relay 121 to the grounded conductor 146.

When relay 121 is operated at the beginning of the first impulse of the series it 85 closes a circuit from battery through its left-hand winding and left contact, conductor 148, outer right back contacts of counting relays 136, 135, 134, 133, 132, 131, 130, 129, 128 and 127 in series, winding of relay 90 127, left back contact of relay 128, conductor 151, lowermost contact of relay 124, upper front contact of relay 123, upper back contact of relay 124, to the grounded conductor 146. Relay 127, however, does not 95 operate in this circuit since it is shunted by the direct path previously traced through the left-hand winding of relay 121 to ground at the inner right contact of relay 120. At the end of the first impulse, the 100 line circuit is closed, relay 115 operates and replaces the shunt around relay 120 and this latter relay becomes deenergized. Relay 120 on deenergizing, opens the shunt around the counting relay 127 and relay 127 operates. 105

It should be noted at this point that the armatures and contacts of the counting relays 127 to 136, inclusive, are so designed that the inner right armature of each of these relays makes connection with its contact slightly in advance of the time that the outer right-hand armature disengages its back contact. By this arrangement, the inner right-hand armature of relay 127, for example, closes its front contact before the 110 operating circuit of said relay is opened at the outer right-hand armature and back contact.

Relay 127 locks in a circuit traceable from battery, through the resistance 125, inner right armature and contact and winding of relay 127, left back contact of relay 128, conductor 151, lowermost contact of relay 124, upper front contact of relay 123, upper contact of relay 124 to the grounded conductor 146. 125

When the relay 120 releases at the termination of the impulse and removes the shunt around the winding of relay 127, the resistance of this relay 127 is thrown in 130

series with the left-hand winding of relay 121. The increase of resistance causes a corresponding decrease in the current flow through the left-hand winding of relay 121.

5 Immediately following, the inner right-hand armature of relay 127 makes engagement with its contact and maintains this engagement for an interval before the outer right-hand armature disengages its back contact. During the interval mentioned, the left-hand winding of relay 121 is shunted by the holding circuit above traced from battery, through resistance 125 and the winding of relay 127 to ground. The shunting 10 effect produces a still further reduction in the flow of current in the left-hand winding of relay 121. At the end of the interval, the outer right-hand armature and back contact of relay 127 open completely the circuit 15 through the left-hand winding of relay 121.

The windings of relay 121 are arranged differentially with respect to each other. The magnetic flux set up by the left-hand winding is sufficient to maintain the armatures attracted in opposition to the magnetic flux set up by the right-hand winding, even when the flow of current through said left-hand winding has been reduced as above described. However, a double reduction of 20 current through the left-hand winding of relay 121 decreases the resultant flux to such an extent that when the circuit through the left-hand winding is completely open, the relay due to its differential character, releases quickly.

Thus, at the end of the first impulse, relay 127 is energized and locked depending on the back contact of relay 128, relay 120 is deenergized and relay 121 is also released.

40 The relays 119 and 122 have their circuits intermittently opened and closed during the series of impulses, but, being slow-to-release, they maintain their armatures attracted during these brief interruptions.

45 When the second and last impulse of the series is received, relay 115 releases and relay 120 is again operated. Relay 120 completes the circuit above described for the left-hand winding of relay 121 and this latter relay attracts its armatures. Relay 121 in operating, recloses the circuit of relay 122 and also completes a path from battery through its left-hand winding and left contact, conductor 148, outer right back contact, conductor 149, outer right front contact of relay 127, winding of relay 128, outer left contact of relay 129 to the grounded conductor 151. Relay 128, however, does not operate at this time due to the shunt maintained at the inner right contact of relay 120. At the end of the second impulse, relay 120 becomes deenergized and removing the shunt permits the counting relay 128 to operate in series 55 with the left-hand winding of relay 121.

Relay 128 locks in a circuit from battery through the resistance 125, inner right front contact of relay 128, winding of said relay, outer left back contact of relay 129 to the grounded conductor 151. Relay 128 at its 70 left back contact opens the circuit of relay 127 and this latter relay releases. In the manner already described, relay 128 causes a double reduction in the flow of current through the left-hand winding of relay 121 75 and also opens this circuit thereafter to permit the relay 121 to release.

After the usual interval has expired following the first series of impulses, relay 122 having its circuit opened, retracts its armature. Relay 122 completes a circuit from ground over the conductor 146 through its contact, lower front contact of relay 123, inner lower contact of relay 124, conductor 144, left back contact of relay 205, winding 80 of relay 204, to battery. Relay 204 operates and closes a circuit from battery, through its winding and right contact, conductor 145, winding of relay 124, lower contact of relay 123, contact of relay 122, to ground over 85 conductor 146. Relay 124 does not operate in this circuit since it is shunted by the original operating circuit for the relay 204. Relay 204 at its left contacts extends the conductors from the counting relays through to 90 the relays 206, 207, 208 and 209 of register 95 200.

Since the second counting relay 128 is operated, representing the first digit of the designation, a circuit is completed from 100 ground over the conductor 151 as above traced through the left front contact of relay 128, conductor 142, next to the outermost left contact of relay 204, winding of register relay 208 to battery. Relay 208 operates and locks in a circuit from battery through its winding and inner left contact to ground over conductor 146. Relay 208 establishes a circuit from ground over conductor 146 through its outer left contact, winding of relay 205 to battery. Relay 205 at its left back contact opens the shunt around relay 124 and this latter relay operates in series with relay 204. Relay 124 at its lowermost contact opens the holding circuit of relay 128 105 permitting this relay to release. Relay 124 at its upper contact, opens the holding circuit of relay 123. Relay 123 releases and in so doing opens the circuit of relays 124 and 204. Relay 124 releases, restoring the 110 impulse receiving mechanism and relay 204 becomes deenergized to disconnect the counting relay set 126 from the register relays 200.

The subscriber now manipulates his dial 150 to transmit a series of three impulses 115 representing the second digit of the designation. As already explained, the transmission of two impulses causes the operation of relay 127, the operation of relay 128 and the release of relay 127. When the third and 120 125 130

- last impulse is transmitted, the relay 121 operates in the manner explained and completes the following circuit: battery through the left-hand winding and left contact of relay 121, conductor 148, outer right contacts of relays 136 to 129 inclusive, outer right front contact of relay 128, winding of relay 129, left back contact of relay 130, to ground over conductor 151. It will be noted that 5 relay 123 operates and locks on the first impulse of the second series in the manner already explained. Relay 129 in operating, closes a locking circuit to battery through resistance 125, inner right contact of relay 10 129, left back contact of relay 130 to ground over conductor 151. Relay 129 at its outer left back contact opens the circuit of relay 128 and this latter relay deenergizes. 15
- After a sufficient interval has elapsed following the second series of impulses, the slow relay 122 again releases and a circuit is closed from ground over conductor 146, contact of relay 122, lower contact of relay 123, inner lower contact of relay 124, conductor 144, left front contact of relay 205, conductor 220, left back contact of relay 212, winding of relay 213, to battery. Relay 213 operates and closes a circuit from battery through its winding and right contact, conductor 145, thence as above traced through the winding of relay 124 to the grounded conductor 146. Relay 124 being shunted does not operate until the relay 212 attracts its armature at a later time. Relay 213 at 25 its left contacts extends the control conductors from the counting relays 126 through to the relays 214, 215, 216 and 217 of the second register 201.
- Since the third counting relay 129 is operated in response to the second series of impulses, a circuit is closed from the grounded conductor 151 through the outer left front contact of relay 129, conductor 148, outermost left contact of relay 213, winding of 30 the relay 214 to battery. Relay 214 operates and locks in a circuit from battery through its winding and inner left contact to the grounded conductor 146. Still another circuit is established from ground over conductor 151, through the inner left contact of relay 129, conductor 142, next to the outermost back contact of relay 213, winding of register relay 216 to battery. Relay 216 actuates and locks through its winding and 35 inner left contact to the grounded conductor 146. Relay 212 is now energized in the following circuit: battery, through the winding of relay 212, outer left contacts of relays 214 and 216 in parallel to the grounded conductor 146. Relay 212 locks through its right contact to the conductor 146. Relay 212 at its left back contact opens the shunt around relay 124 and relay 124 energizes in 40 series with relay 213. Relay 124 opens the

circuit of relay 123 which in turn releases 65 and opens the circuit of relays 124 and 213. Relay 213 disconnects the counting relay set 126 from the register relay 201.

In a manner identical to that described, other series of impulses may be transmitted 70 over the calling line representing other digits of the designation which are received and recorded upon succeeding registers similar to those shown in Fig. 2. A third register 203 is schematically illustrated in which the 75 relay 219 corresponds to relays 205 and 212 of the first two registers.

The variable settings of these registers represent the different digits of the wanted 80 designation and circuits controlled by said registers may be closed in a manner well known in the art for determining the selective operations of the switches. For example, the register 200, 201, etc., may determine the selection of the magnets 113, 114, 85 etc., to choose the required trunks outgoing from the switch 106, as shown in the patent to S. B. Williams, No. 1,517,331, issued December 2, 1924.

When the last digit has been recorded on 90 the register, a circuit may be closed for the relays 210 and 218 in any desired manner as illustrated in the said patent to S. B. Williams. Relays 210 and 218 merely serve to apply ground potential to the different contacts of the register relays to determine the selection of the circuit represented by the setting of the registers. In connection with the register 200, the selecting circuit leads from ground through the 100 contact of relay 210, right front contact of relay 208, inner right back contact of relay 206, innermost left back contact of relay 207 to the selecting conductor 252.

For the register 201, the selecting circuit 105 may be traced from ground through the inner contact of relay 218, right front contact of relay 216, innermost right front contact of relay 214, next to the inner left back contact of relay 215 to the selecting conductor 253. In a similar manner, the selecting circuits for the remaining relay registers (not shown) are also completed. Inasmuch 110 as the present invention relates more particularly to the arrangement and functions of the counting relay set shown in Fig. 1, it has not been considered necessary to illustrate in detail the method of control which the several registers exercise over the switches. In fact, as already explained, any of the well known methods wherein automatic switches are controlled selectively by the registration, may be employed.

Thus far only the first three counting relays 127, 128 and 129 have been operated accounting for series up to three impulses in 120 number. In order to illustrate the further operations of the counting relays, a descrip- 125

tion will now be given of the apparatus in response to series of impulses representing the remaining seven digits.

Assume that a series of four impulses is received. The operation is the same as already described for the first three impulses. Upon receipt of the fourth and last impulse of the series, relay 121 operates and closes a circuit from battery through its left-hand winding and left contact, conductor 148, thence through the outer right back contacts of relay 136 to 130 inclusive, outer right front contact of relay 129, winding of relay 130, left back contact of relay 131 to ground over conductor 151. At the end of the impulse when relay 120 releases, relay 130 operates and locks through its inner right contact and also causes the release of relay 121. Relay 130 at its left back contact, opens the circuit of relay 129.

If a series of five impulses are transmitted, the fifth impulse causes in the manner explained, the operation of relay 121. Relay 121 closes the circuit above traced through its left-hand winding and contact, thence over conductor 148 through the outer right contacts of relays 136 to 131, inclusive, outer right front contact of relay 130, winding of relay 131, left back contact of relay 136, conductor 151, to ground. At the end of the impulse when relay 120 releases, relay 131 operates and in turn causes the release of relay 121. Relay 131 becomes locked in a circuit from battery through resistance 137, inner right contact and winding of relay 131, left back contact of relay 136, conductor 151 to ground. Relay 131 at its left back contact opens the circuit of relay 130 and this latter releases.

If a series of six impulses are transmitted, the relay 121 in energizing on the beginning of the sixth impulse completes a circuit from battery through its left hand winding and left contact, conductor 148, outer left back contacts of relays 136 to 132 inclusive, outer right front contact of relay 131, winding of relay 132, left back contact of relay 133, to the grounded conductor 151. At the end of the impulse, relay 120 releases, and removing the shunt, permits relay 132 to operate in series with the left winding of relay 121. Relay 132 causes the deenergizing of relay 121 in the manner described. It should be noted, however, that relay 132 in operating does not cause the preceding relay 131 to release as has been the case up to this point. Thus, at the end of a series of six impulses both relays 131 and 132 are energized and locked. The locking circuit for relay 132 may be traced from battery through the resistance 138, inner right contact and winding of relay 132, left back contact of relay 133 to the grounded conductor 151.

When a series of seven impulses are trans-

mitted, relay 121 on operating at the beginning of the seventh impulse closes a circuit through its left-hand winding and contact over conductor 148, through the outer right back contacts of relays 136 to 133 inclusive, outer right front contact of relay 132, winding of relay 133, outer left back contact of relay 134 to ground over conductor 151. At the end of the impulse, relay 120 releases and permits relay 133 to operate in series with relay 121. Relay 133 causes the relay 121 to release and also closes a locking circuit for itself as follows: battery, through resistance 138, inner right contact and winding of relay 133, outer left back contact of relay 134 to the grounded conductor 151. Relay 133 at its left back contact opens the holding circuit of relay 132. Relay 132 releases. It will be noted that relay 131 still remains energized.

When a series of eight impulses are transmitted, relay 121 in operating on the eighth impulse closes a circuit, similar to that already described, for the counting relay 134. Relay 134 operates at the end of the eighth impulse and closes a locking circuit for itself from battery, through resistance 138, inner right contact and winding of relay 134, left back contact of relay 135 to ground over conductor 151. Relay 134 at its outer left back contact severs the holding circuit of relay 133. Relay 133 releases but relays 131 and 134 remains energized.

Should the subscriber send a series of nine impulses, the relay 121 in operating on the ninth impulse completes an analogous circuit for the next counting relay 135. Relay 135 operates at the end of the impulse and closes a holding circuit for itself from battery through the resistance 138, inner right contact and winding of relay 135, left back contact of relay 136 to ground over conductor 151. Relay 135 causes the release of relay 121 and also opens at its left back contact, the holding circuit of relay 134. Relay 134 deenergizes and relays 131 and 135 remain locked.

If a series of ten impulses are transmitted, the relay 121 responding to the last impulse closes a circuit from battery through its left-hand winding and contact, conductor 148, outer right contact of relay 136, outer right front contact of relay 135, winding of relay 136 to ground over conductor 151. At the end of the impulse when relay 120 releases, relay 136 operates and causes the deenergization of relay 121 in the manner explained. Relay 136 closes a locking circuit from battery through the resistance 138, inner right contact and winding of relay 136 to the grounded conductor 151. Relay 136 at its left back contact opens the holding circuits of relays 135 and 131. Thus, at the end of a series of ten impulses, relay

136 remains energized and all proceeding relays are released.

From inspection, it will be observed that the several relays of the registers 200, 201, 5 etc., are operated in different combinations when different ones of the counting relay set 126 are energized. The following is a table showing the counting relays operated, the conductors grounded, and the register 10 relays of the register 200 energized for the several series of impulses:

Number of impulses	Counting relays energized	Conductors grounded	Register relays energized
1	127	148	206
2	128	142	208
3	129	143, 142	206, 208
4	130	141	209
5	131	140	207
6	131, 132	143, 142	206, 207
7	131, 132	142, 140	208, 207
8	131, 134	143, 142, 140	206, 205, 207
9	131, 135	141, 140	209, 207
0	136	139	211

It may be noted that the first register 25 200 is arranged to automatically erase the digit 1 in order to guard against the recording of an accidental impulse. This is accomplished by making the locking circuit of relay 206 dependent upon the energization of either one or more of the relays 207, 208 and 209. If a single impulse is sent, the relay 206 operates in response thereto, but since neither of the three relays is operated and since relay 205 cannot lock the relay 206 releases immediately that the counting relays become deenergized. Referring to the register 201, it will be noted that the digit 1 may be recorded since the relay 214 locks directly to the grounded 40 conductor 146.

Since it may be necessary to release the relay 205 following an accidental impulse in order that the first series of impulses is recorded on the register 200 instead of passing on to the next register 201, this relay is not provided with a locking circuit. Accordingly it is not available for recording the digit 0 as is the case in the other registers. Therefore an additional relay 211 is provided for recording the digit 0 or ten impulses. Referring to the next register 201, since the relay 212 once energized always remains energized until the equipment is released, this relay may therefore be used for recording the digit 0. When ten impulses are transmitted, the relay 212 responds thereto and locks to the grounded conductor 146. In this case, none of the other four relays 214, 215, 216 or 217 is operated. Accordingly, a circuit may be traced for the zero operating lead through back contacts of these four relays.

When the recording mechanism is no longer required, the circuit of relay 115 is opened as by releasing the switch 105 and

relay 115 becomes deenergized. Relay 115 opens the circuit of relay 119, which, after an interval, retracts its armatures. Relay 119 removes the ground potential from conductor 146 and all energized relays in the 70 controlling and register circuits are released.

What is claimed is:

1. In combination, a series of relays arranged to operate successively in response to a series of impulses, a plurality of said 75 relays each having means for releasing the preceding relay when it is operated, and means when a particular one of said series of relays is operated for maintaining such relay operated until a plurality of succeeding 80 relays have been operated.

2. In combination, a series of counting relays arranged to operate successively in response to a series of impulses, means for releasing a number of said relays while impulses are being received, and means when a particular one of said series of relays is operated for maintaining said relay operated until a plurality of succeeding 85 relays are operated and released. 90

3. In combination, a series of counting relays arranged to operate one after another in response to a series of impulses, a number of said relays each having means for releasing the preceding relay when it is operated, means when a certain one of said series of 95 relays is operated for maintaining said relay operated during the operation of a plurality of succeeding relays, and means for releasing said certain relay when a particular succeeding relay is operated. 100

4. In combination, a single series of counting relays arranged to be operated one after the other in response to a series of impulses, each of a certain number of said 105 relays arranged to release upon the termination of the impulse causing the energization of the next succeeding relay, and means when a particular one of said series of relays is operated for maintaining such relay operated until a plurality of succeeding 110 relays have been operated and released. 110

5. In combination, a series of counting relays arranged to be operated in succession in response to a series of impulses, each of a number of said relays having means for releasing the preceding relay when it is operated, means for releasing a particular one of said series of relays only after a plurality 115 of succeeding relays have been operated, and a selection controlling device controlled by 120 said relays. 120

6. In combination, a series of counting relays arranged to operate successively, a differential relay responsive to series of impulses for causing the operation of said 125 counting relays, each of a plurality of the counting relays having means for releasing the preceding relay when it is operated, and means when a particular one of the series 130

of relays is operated to maintain such relay operated until a plurality of succeeding relays have been operated, said differential relay having two windings one of which is controlled by said counting relays.

7. In combination, a series of relays arranged to operate successively in response to a series of impulses, each of a plurality of said relays having means for releasing 10 the preceding relay when it is operated,

means when a particular one of the series of relays is operated to maintain it operated until a plurality of succeeding relays are operated, and registers set by said series of relays to establish registrations.

15

In witness whereof, I hereunto subscribe my name this 24th day of October, A. D. 1922.

SAMUEL B. WILLIAMS, JR.
